UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

UNDERFEED STOKER.

Application filed May 10, 1923. Serial No. 638,118.

This invention relates to multiple retort underfeed stoker furnaces in which fuel-feeding retorts and rows of tuyères are alternately arranged in parallel relation and 5 inclined downwardly from the front wall of the furnace toward the dump grate, and it has for an object to provide a grate surface composed of parts of simple and durable construction which may be readily assembled or replaced without materially disturbing other parts of the grate.

Another object of the invention is to provide a retort constructed of fabricated frame members upon which detachable side 15 and bottom plates are mounted, thereby obtaining the advantage of the superior strength and durability of structural iron or steel frames over the usual cast iron retorts which tend to warp and crack under 20 the weight and heat of the tuyères and fuel bed usually supported by the retorts. By making the supporting frame, the side and bottom walls and the tuyère banks detachable and sectional, any part may be removed 25 in case of failure without necessitating the removal of the retorts and without disturbing any other parts, except possibly parts contiguous to the part to be replaced.

A further object of my invention is to 30 provide a retort frame which shall carry the refuse discharging mechanism or dump grate at the rear of the underfeed grate and which shall carry the ram box and hopper casting at the front of the retorts. The lateral strains imposed upon the dump grate 35 and ram box supports are quite severe and frequently cause failure of the cast iron retorts usually employed to support them in position, since the retorts are subjected to 40 uneven temperatures and rapid temperature variations and are taxed to their full capacity in supporting the tuyères and fuel bed resting thereupon. The structural or fabricated retort frames of the present invention are enabled to withstand the strains 45 imposed upon them by the refuse discharging and the fuel-feeding mechanisms and by the load of the fuel bed, and are also better adapted to withstand the temperature variations incident to the operation of high duty 50 furnaces without deformation or failure of the supporting elements.

These and other objects are attained by means of a stoker construction embodying 55 the features herein described and illustrated

in the drawings accompanying and forming a part hereof wherein Fig. 1 is a view in side elevation of a unit of an underfeed stoker embodying my invention; Fig. 2 is a fragmentary plan view of a plurality of 60 units, parts of the stoker structure being omitted to show the retort frame; Figs. 3 and 4 are fragmentary views in section taken on lines III—III and IV—IV, respectively, of Fig. 1; Fig. 5 is a fragmentary view in section of the splice plate joining the sections of the retort side plates; 65 Figs. 6 and 7 are views in transverse section taken through a ram box on lines VI—VI and VII—VII, respectively, of Fig. 1; and Fig. 8 is a fragmentary view in longitudinal section through the center of the ram box and retort, and Fig. 9 is a perspective view of a front frame member employed in 70 supporting the retort frame and showing 75 the retort frame in place.

Referring to the drawings, I show an underfeed stoker composed of a plurality of units 10 disposed in side-by-side relation upon front and rear transverse beams 11 80 and 12. Each unit comprises a retort frame consisting of a front frame member 15 and a rear frame member 16, supported on the transverse beams 11 and 12, respectively, and in length equal to the distance between 85 the axes of the adjacent tuyère banks 17 when the units are in assembled position. Two beam members 18 extend longitudinally of the retort frame and are secured to the end frame members 15 and 16 in a manner 90 hereinafter described.

The front frame member 15 consists of a single casting of U section, viewed from the end, the U facing rearwardly of the stoker. The casting is provided with a pair 95 of transversely extending webs 20 spaced away from the ends thereof. Between the webs 20 are formed a pair of slots 21 for the reception of the beam members 18, and having at their bases a pair of supporting 100 lugs 22. The slots 21 are spaced apart a sufficient distance for the beam members 18 to provide the proper width for the retort 10. The beam members extend forwardly beyond the member 15 as shown in Figs. 1, 105 8 and 9.

The rear retort frame member 16 has a rear wall 25, which closes the end of the retort frame against air leakage to the ash pit, spaced webs 26 and end webs 27. The 110

webs 26 are disposed so as to form abutments to which the beam members 18 are secured. The spacing of the webs 20 of the front frame member 15 and of the webs 26 5 of the rear frame member 16 is such as to secure a parallel relation of the beams 18.

The beam member 18, as shown, is in the form of an angle-iron having a vertical web and a horizontal web, the horizontal webs 10 of a pair of angle-irons extending inwardly to form ledges upon which side retort plates 30 are carried. Each retort side is made up of a number of plates 30 secured to each other and to the angle-iron 18. A strong 15 juncture of the plates is effected by the employment of a splice plate 31, which lies in an inset in the meeting edges of the plates, in order to produce a smooth interior surface for the retort, and clamp plates 32 exterior to the joint. Bolts 33 passing through splice plate 31, side wall plates 30, angle-iron 18 and clamp plate 32, cooperate with the bolts 34 near the upper edge of the plates to hold the side wall plates 30 of the retort 20 rigidly in place.

The side plates 30 are provided with longitudinally extending ribs 36 upon which are disposed bottom plates 37. The ribs 36, as shown, extend at angle to the upper 30 edges of the side plates 30 in such a manner as to form a retort of decreasing depth. The upper edge of each plate 30 is provided with a notched flange 39 which serves to support the tuyère plates 17 in place.

35 The portions of the angle-irons 18 which extend forwardly of the front frame member 15 carry a ram box casing 40 which, as shown in Figs. 6, 7, and 8, is provided at its forward end with legs 41 which rest 40 upon the angle-irons 18 and are secured thereto by bolts 42, and at its rear end has a rectangular base 44 which fits into the channel support formed by the angle-irons and is secured thereto by studs 45.

45 Reinforcing members 50 are disposed on either end of the front frame member 15 and serve to hold the upper free ends of the foremost side wall plates 30 rigidly in position. The reinforcing members 50 are preferably bolted to the frame member 15, angle-irons 18 and side plates 30 for this purpose. The reinforcing members 50, furthermore, form abutments against which the ram box casting 40 is held, and thus a tight closure 55 is effected between the ram box and the retort.

A dump grate section 55 may be supported from the rear frame member 16 which, as shown, in Figs. 1 and 2, is provided with 60 rearwardly extending brackets 56 in which the shaft 57 of the grate is carried. The dump grate section is preferably of the same width as the length of the rear frame member 16.

65 From the above description it is seen that

I have provided a unit which embraces the principal elements of an underfeed stoker, and that all of the parts thereof are carried by a retort frame composed of but four members to wit: front and rear frame members 15 and 16 and two longitudinally extending beams 18. Upon this fabricated retort frame, the ram box, the retort side walls, the retort bottom walls, and the dump grate are carried. The assembly of a plurality of these units in side-by-side relation upon the transverse beams 11 and 12 and the disposition of the tuyère banks upon the retort side walls of adjacent sections permits the formation of stokers of various widths.

70 While I have shown my invention in but one form, it will be obvious to those skilled in the art that it is not so limited, but is susceptible of various other changes and 75 modifications without departing from the spirit thereof, and I desire, therefore, that only such limitations shall be placed thereupon as are imposed by the prior art or as are specifically set forth in the appended 80 claims.

85 What I claim is:

1. In an underfeed stoker having a combustion grate formed of alternately disposed retorts and tuyère rows, a retort frame comprising a front end member, a rear end member, each said member being equal in length to the distance between the axes of adjacent tuyère rows of the assembled combustion grate, beam means extending from the rear member to the front member and means for securing the beam means to said end members, whereby the said end members protrude beyond the beam means to serve as spacers for an assembly of retort frames. 100

105 2. In an underfeed stoker having a combustion grate formed of alternately disposed retorts and tuyère rows, a retort frame comprising a front end member, a rear end member, each said member being equal in length to the distance between the axes of adjacent tuyère rows of the assembled combustion grate, beam means extending from the rear member to the front member, means for securing the beam means to said end members, whereby the said members protrude beyond the beam means to serve as spacers for an assembly of retort frames, and reinforcing members disposed above and secured to the beam means and to the protruding portions of said front end member. 115

120 3. In an underfeed stoker having a combustion grate formed of alternately disposed retorts and tuyère rows, a retort frame comprising a front end member, a rear end member, each said member being equal in length to the distance between the axes of adjacent tuyère rows of the assembled combustion grate, two parallel beam members 125 extending from the rear member to the front 130

- member, and means for securing the beam members to said end members, whereby the end members protrude beyond the beam members to serve as spacers for an assembly 5 of retort frames.
4. In an underfeed stoker having a combustion grate formed of alternately disposed retorts and tuyère rows, a retort frame comprising a front end member, a rear end member, two parallel beam members extending from the rear member to the front member, the front end member having intermediately spaced inwardly-extending openings in which the beam members rest, and the rear 10 end member having centrally spaced ribs to which the rear ends of the beam members are secured, and means for securing all the said members together to form a rigid retort frame.
- 15 5. In an underfeed stoker having a combustion grate formed of alternately disposed retorts and tuyère rows, a retort frame comprising a front end member, a rear end member, two parallel beam members secured to said end members and extending forwardly of the front end member and a ram box mounted on said beam members forwardly of the front end member.
- 20 6. In an underfeed stoker having a combustion grate formed of alternately disposed retorts and tuyère rows, a retort frame comprising a front end member, a rear end member, two parallel beam members, and means for securing the beam members to central 25 portions of said end members, the beam members extending forwardly of the front end member and a ram box mounted on said beam members forwardly of the front end member.
- 30 7. In an underfeed stoker having a combustion grate formed of alternately disposed retorts and tuyère rows, a unit retort comprising a frame having a front end member, a rear end member, and two parallel beam members extending from the rear member to the front member, plates carried by said beam members to form the retort side walls, said plates having integrally formed ribs thereon, and plates carried by said ribs and disposed between the side wall plates to form 35 the bottom of the retort.
- 40 8. In an underfeed stoker having a combustion grate formed of longitudinally extending retorts supporting parallel rows of tuyère plates therebetween, a unit section comprising a retort frame having a front end member, a rear end member, two beam members therebetween and means for securing said beam members to intermediate portions of said end members; plates carried by the beam members to form retort side walls; plates carried by and disposed between said side wall plates to form a retort bottom; and a ram box member, said beam 45 members extending forwardly of the front 50 member, and means for securing said beam members to said end members.
- 55 9. In an underfeed stoker having a combustion grate formed of longitudinally extending retorts supporting parallel rows of tuyère plates therebetween, a unit section comprising a retort frame having a front end member, a rear end member, two beam members therebetween and means for securing said beam members to said end members; plates carried by the beam members to form retort side walls; plates carried by and disposed between said side wall plates to form a retort bottom; a ram box member, said beam members extending forwardly of the front 60 member, and means for securing said beam members to said end members.
- 65 10. In an underfeed stoker having a combustion grate formed of longitudinally extending retorts supporting parallel rows of tuyère plates therebetween, a unit section comprising a retort frame having a front end member, a rear end member, each said member being equal in length to the distance between the axes of adjacent tuyère rows of the assembled combustion grate, means for securing the beam means to said end members intermediate the tuyère rows, whereby the said members protrude beyond the beam means to serve as spacers for an assembly of retort frames and reinforcing members disposed above and secured to the protruding portions of said front end member, and a ram box member, said beam members extending forwardly of the front end members and supporting said ram box member in position in contact with the forwardly disposed faces of said front end member and said reinforcing members.
- 70 11. An underfeed stoker including a plurality of units disposed in side-by-side relation, each unit comprising a retort frame having a front end member, a rear end member, two beam members therebetween and means for securing said beam members to said end members; plates carried by the beam members to form retort side walls; plates carried by and disposed between said side wall plates to form a retort bottom; and tuyère members extending between and carried by the upper edges of the side wall plates of adjacent sections.
- 75 12. An underfeed stoker including a plurality of units disposed in side-by-side relation, each unit comprising a retort frame having a front end member, a rear end member, two beam members therebetween; plates carried by the beam members to form retort side walls; plates carried by and disposed between said side wall plates to form a retort bottom; each said end member being equal in width to distance between the 80 85 90 95 100 105 110 115 120 125 130

- axes of adjacent tuyère rows of the assembled combustion grate, means for securing the beam means to said end members intermediate the tuyère rows, whereby the said 5 members protrude beyond the beam means to serve as spacers for an assembly of retort frames, reinforcing members disposed above and secured to the protruding portions of said front end member, and a ram 10 box member, said beam members extending forwardly of the front end member and supporting said ram box member in position in contact with the forwardly disposed faces of said front end member and said reinforcing members.
13. An underfeed stoker including a plurality of units disposed in side-by-side relation, each unit comprising a retort frame having a front end member, a rear end 20 member, two beam members therebetween and means for securing said beam members

to said end members; plates carried by the beam members to form retort side walls; plates carried by and disposed between said side wall plates to form a retort bottom; tuyère members extending between and carried by the upper edges of the side wall plates of adjacent sections; a transverse beam supporting the rear end members of the several sections, means for securing the rear end members in contiguous relation one to the other, a transverse beam supporting the front end member, and means for securing the front end members in contiguous relation one to the other, whereby the stoker when assembled forms a rigid fabricated whole which is carried upon the two said transverse beams.

In testimony whereof, I have hereunto subscribed my name this 7th day of May 40
1923.

OTTO ARAM.
